UNITED STATES PATENT OFFICE.

ROWLAND WESTON, OF EAST SAGINAW, MICHIGAN.

WATER-CLOSET.

SPECIFICATION forming part of Letters Patent No. 405,635, dated June 18, 1889.

Application filed August 18, 1888. Serial No. 283,090. (No model.)

To all whom it may concern:

Be it known that I, ROWLAND WESTON, of East Saginaw, in the county of Saginaw and State of Michigan, have invented new and useful Improvements in Water-Closets, of which the following is a description.

My invention relates to an improvement in water-closets, and has for its object to provide a closet of simple and effective construction, 10 which may be left unattended for any length of time and remain filled with water; and a further object of the invention is to provide a simple means for automatically discharging water from the flushing-tank into the bowl 15 should the latter become empty through evaporation or otherwise.

The invention consists in the construction and combination of the several parts, as will be hereinafter fully set forth, and pointed out 20 in the claims.

Reference is to be had to the accompanying drawings, forming a part of this specification, in which similar figures of reference indicate corresponding parts in all the views.

25 Figure 1 is a central vertical section through the flushing-tank, illustrating the valve as closed. Fig. 2 is a central vertical section through the bowl. Fig. 3 is a central vertical section through the flushing-tank, illustrating 30 the valve as open to admit water to the bowl; and Fig. 4 is a front elevation of the bowl, partly broken away.

In carrying out the invention the bowl 10 is made double at the upper edge to provide 35 an annular chamber 11, in the lower wall of which chamber a series of perforations 12 is produced. A vertical extension 13 is built upon the rear of the bowl, which extension joins the upper edge of the same, whereby a 40 chamber 14 is formed intersecting the upper annular chamber 11. The chamber 14, I designate, for convenience, the "flushing-chamber." The wall of the bowl proper constitutes the inner wall of the chamber 14, and 45 in the said wall near the bottom one or more apertures 15 are made to admit water to the said bowl.

The bowl 10, with the exception above noted, may be of any desired construction, being 50 provided with a trap-valve 16, operated by a weighted lever 17, or otherwise, as desired.

In the rear wall of the flushing-chamber, at or near its bottom, a neck is formed, and to said neck a flushing-pipe 18 is coupled, which pipe is carried upward to a connection with 55 the flushing-tank 19. The flushing-tank is provided with a water-supply pipe 20, preferably entering it at the end opposite to that receiving the flushing-pipe, and the exit of the water from the supply-pipe is controlled 60 by the usual float-valve 21, as shown in Fig. 1.

A valve-seat 22 is introduced in the bottom of the tank, consisting of a thimble 23, having a flanged or cup-shaped head 24, and the said valve-seat is so located that the body of 65 the thimble will enter the flushing-pipe, or the said pipe be coupled thereto, and the head rest upon the bottom of the tank, as best shown in Fig. 1.

The valve 25, consisting of a disk 26, of 70 greater diameter than the head of the thimble, constitutes the seat, which disk is secured in any approved manner to the under surface of a preferably cylindrical float 27. The valve 25 is completed by attaching a 75 smaller disk 28 to the aforesaid disk 26, adapted to close the opening of the thimble-body, and the addition to the smaller disk of a section of pipe 29, having a series of vertical 80 slots cut from the bottom upward.

The slotted pipe-section 29 is purposed to slide in the body of the thimble. A second float 30 is held a distance above the float 27 by a tubular post 31, attached to and extending through the lower float to a connection 85 with the pipe-section 29. The two floats and the valve are adapted to have a vertical movement, and are guided in said movement by a pin 32, integral with the upper float, passing upward between two spaced guide- 90 rods 33, secured to the upper edge of the tank.

The bowl when not in use is about half filled with water, which covers the opening 15, and as long as the said opening remains 95 covered the column of water in the flushing-pipe remains intact. When, however, the trap-valve 16 is opened, the water in the bowl, running out, uncovers the opening 15, and the water in the flushing-pipe floods the 100 chambers 14 and 11, and passes from thence to the bowl, and as the water in the flushing-

pipe escapes the suction of the same is removed from the valve, and as the valve is held closed by said suction the balance of the floats 27 and 30 is broken, and said floats rise and unseat the valve, the upper float touching the top of the tank. The floats remain elevated until sufficient water passes out to fill the flushing-pipe, whereupon the valve again closes, the water in the bowl 10 having in the meanwhile risen above the aperture 15.

The upper float 30 will prevent overflow from the tank should the ball-valve 21 refuse to act, as the said float 30 will raise the valve 15 25 and the water will pass down into the bowl, which may be provided with an overflow.

A small pipe 34 may, if desired, be located in the tank, one end whereof extends above 20 the tank, and the other end is located beneath the valve 25. The purpose of the said pipe is to admit air to the tank and valve to operate the floats. The pipe can be kept closed and operated by a push-button.

Having thus described my invention, I claim as new and desire to secure by Letters Patent—

1. The combination, with the bowl having a valve normally closing its outlet, of a stand-pipe communicating with the bowl below the 30 water-level and normally filled with water, a tank from which the upper end of the stand-pipe leads, and a float-valve in the tank completely closing the upper end of the stand-pipe against air or water, whereby said valve will be held closed by the suction exerted by the column of water in the stand-pipe, released when the bowl is emptied to again fill the stand-pipe, and be closed by its weight when the water in the tank is insufficient to float it, substantially 35 40 as set forth.

2. The combination, with the water-closet bowl having a trap-valve normally closing its outlet to hold the water in the bowl and an aperture below the water-line, of a normally-filled stand-pipe communicating with the bowl 45

through said aperture, a tank with the bottom of which the upper end of the stand-pipe communicates, a float-valve normally closing the said upper end of the pipe against the entrance of either air or water and held in its closed position against its tendency to rise by the suction caused by the weight of the water in the stand-pipe, and a supply-pipe leading into the tank and having a float to close it when the water reaches its proper level, the 50 55 said float-valve being released by the exit of the water from the bowl, floating or held buoyant until the tank has sufficiently discharged, and then closing by its weight to be again held closed by the action of the water in the stand-pipe, substantially as set forth.

3. In a water-closet, the combination, with a bowl, a vertical extension produced upon the rear of the same, forming a flushing-chamber provided with an outlet at the bottom 65 leading into the bowl, a tank, and a pipe connecting the tank and flushing-chamber, of two connected spaced floats in said tank, a guide attached to the upper float, and a valve secured to the under side of the lower float 70 adapted to close the flushing-tube, substantially as shown and described.

4. In a water-closet, the combination, with a bowl, a vertical extension produced upon the rear of the same, forming a flushing-chamber provided with an outlet in the bottom 75 leading into the bowl, a tank, and a pipe connecting the tank and flushing-chamber, of a cup-shaped valve-seat above the flushing-tube, two spaced connecting-floats, a guide attached 80 to the upper float, a valve secured to the bottom of the lower float, consisting of disks of different diameters, and a central slotted tube adapted to enter the flushing-pipe, substantially as shown and described.

ROWLAND WESTON.
